LIGHTING FIXTURE GLOBE

Robert H. Ensign, Bronxville, and Charles A. Jerabek,
Bayshore, N. Y., assignors to The Phoenix Glass Com-
pany, Monaca, Pa., a corporation of West Virginia

Application May 2, 1955, Serial No. 35,764

Term of patent 14 years

(Cl. D48—16)

Fig. 1

Fig. 2

Fig. 3

Figure 1 is a bottom perspective view of a lighting fixture globe, showing my new design,

Figure 2 is a bottom plan view thereof to a larger scale, and

Figure 3 is a side elevational view to the same scale as Figure 2.

We claim:

The ornamental design for a lighting fixture globe, as shown.
